217,381

SUPPORT FOR A COFFEE FILTER OR THE LIKE

David Douglas, 1150 Lake Shore Drive,
Chicago, Ill. 60611

Filed Nov. 12, 1968, Ser. No. 14,400

Term of patent 14 years

Int. Cl. D7—99

U.S. Cl. D44—26

FIG. 1 is a top plan view of a support for a coffee filter or the like, showing my design;

FIG. 2 is a side elevational view;

FIG. 3 is a bottom plan view; and

FIG. 4 is a sectional view on line 4—4 of FIG. 1.

I claim:

The ornamental design for a support for a coffee filter or the like, substantially as shown.
